CLAIM

The ornamental design for a pet device, as shown and described.

DESCRIPTION

FIG. 1 is a perspective view of an embodiment of a pet device according to my design;

FIG. 2 is front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

Broken lines having repeated short dashes in the figures are for illustrative purposes only and form no part of the claimed design. Shade lines having a combination of long and short lines in the figures show contour and not surface ornamentation.
